UNITED STATES PATENT OFFICE.

RUSSELL B. PERKINS, OF MERIDEN, CONNECTICUT, ASSIGNOR TO EDWARD MILLER & CO., OF SAME PLACE.

EXTENSION LAMP-FIXTURE.

SPECIFICATION forming part of Letters Patent No. 311,779, dated February 3, 1885.

Application filed August 18, 1884. (No model.)

To all whom it may concern:

Be it known that I, RUSSELL B. PERKINS, of Meriden, in the county of New Haven and State of Connecticut, have invented a new Improvement in Extension-Lamps; and I do hereby declare the following, when taken in connection with accompanying drawings and the letters of reference marked thereon, to be a full, clear, and exact description of the same, and which said drawings constitute part of this specification, and represent, in--

Figure 1, a side view of the hanger; Fig. 2, an end view; Fig. 3, a horizontal section on line *x x* through one of the pivots; Fig. 4, the spring as cut from sheet metal; Figs. 5 and 6, modifications.

This invention relates to an improvement in that class of lamps which are suspended by chains running over pulleys near the ceiling, thence down to the weight, commonly called "library-lamps," and which may be adjusted to various elevations, the weight being employed as a counter-balance for the lamp.

The lamp is usually provided with a glass shade of considerable weight, and the edge of this shade is in some cases provided with rings carrying prisms as an ornament. The weight being suspended over the pulleys and the pulleys free, unless the weight be as much more than the weight of the harp, shade, and lamp, as the weight of the ring and prisms, the application of such ring and prisms over-balances the weight to such an extent that they will not remain in the elevated position.

As these lamps go to the trade they are constructed so that the prism-ring may be applied or dispensed with, according to the requirements of the purchaser. In some cases the prism is required; in others it is not. If the weight be made sufficient to counterbalance the fixture with the prism-ring, then it is heavier than it should be if the prism-ring is omitted.

The object of my invention is to make a cheap and simple balance, whereby the variation made by the presence or omission of the prism-ring may be compensated for; and it consists in the application of friction-springs to the sides of the pulleys, over which the chains run, such springs being applied around

the pivot of the pulley and coupled with the hanger, so as to prevent their rotation with the pulleys, and whereby the spring-pressure is applied directly to the side of the pulley, and as more fully hereinafter described.

A represents the hanger, of usual construction, carrying at each end a pulley, *B*, upon a pivot, *a*, the pivot arranged in downwardly-projecting lugs *C C* on the hanger. The space between the lugs *C C* is considerably more than the thickness of the pulley *B*. The friction-spring is shown detached in Fig. 4. It is made from elastic sheet metal in the form of a cross with a perforation, *b*, in the center, corresponding to the pulley-pivot. The two opposite arms, *D D*, form friction-springs, which are to bear upon the face of the pulley. They are bent into concavo-convex form, as seen in Fig. 2, and so that the extreme ends will bear upon the side of the pulley, while the back will rest against the lug. The other arms, *d d*, of the cross form tongues, which, when the spring is applied, are turned outward against the edge of the lugs, as seen in Figs. 2 and 3, and so as to embrace the sides of the lugs and prevent the spring from rotating with the pulley. The springs thus arranged bear upon the opposite surfaces of the pulley and create considerable friction thereon. Therefore, if the lamp be provided with the usual counter-balancing-weight, the friction only necessitates the application of a little more power in pulling down or raising the lamp, the weight serving to hold it at any point of suspension. This applied friction, however, is sufficient to support the ring and prisms attached when set upon the shade, the springs resisting the downward tendency of such added weight. The springs thus constructed add but a trifling amount to the cost of manufacture, but adapt the fixture to a great range of variation between the weight of the fixture and the counterbalancing-weight.

While I prefer to make the springs in the shape of a cross, so that the two arms may be turned upon the lugs to prevent rotation, the rotation may be prevented without the arms *d d*, say as seen in Fig. 5, the hanger constructed with a rib, *e*, on its face next the

pulley, and the spring constructed, as seen in Fig. 6, with a depression, *f*, in its back corresponding to said rib, and which will interlock with the rib and prevent such rotation.

5 I claim—

1. In a lamp-fixture, the combination of the hanger *A*, by which the fixture is suspended, pulleys *B*, arranged in the respective ends of the hanger, and sheet-metal springs *DD*, arranged upon the pivots of the respective pulleys and between the lugs of the hanger and the side of the pulleys, and so as to bear upon the respective sides of the pulley, the said springs being engaged with the lugs of the hanger to prevent the rotation of the springs, substantially as described.

2. In a lamp-fixture, the hanger *A*, by which the fixture is suspended, combined with the pulleys *B*, hung in the respective ends, and the friction-springs applied at the sides of the pulleys, said springs being substantially cross shape and set upon the pivots of the pulleys, two of the arms forming springs on the side of the pulley, the other two arms bent upon the hanger, and so as to prevent the rotation of the springs with the pulleys, substantially as described.

RUSSELL B. PERKINS.
